UNITED STATES PATENT OFFICE.

TIMOTHY STEBBINS, OF DAVENPORT, IOWA, ASSIGNOR TO RED JACKET MFG. CO., OF DAVENPORT, IOWA, A CORPORATION OF IOWA.

PUMP.

1,226,140.

Specification of Letters Patent.

Patented May 15, 1917.

Application filed November 26, 1915. Serial No. 63,447.

To all whom it may concern:

Be it known that I, TIMOTHY STEBBINS, a citizen of the United States of America, and resident of Davenport, county of Scott, State 5 of Iowa, have invented a certain new and useful Improvement in Pumps, of which the following is a specification.

My invention relates to pumps of the type usually employed for raising water from 10 driven or cased wells, and is directed more especially to double-acting force pumps, and its principal object is the providing of a system of drainage and a method of packing, whereby, with the casing terminating at 15 the ground level, the water cannot rise above or remain above the frost line except during the interval of pumping, and is yet capable of being discharged with full force at the outlet on the first or second stroke of the 20 pump rod, the pump thereby being rendered frost-proof although quick acting. Another object is to provide a construction wherein the casing terminates at the ground level, thus avoiding the necessity of digging a pit 25 to the frost line, an operation often times expensive and laborious, especially in rock formation. Still another object is to provide a construction wherein the employment of the usual "stuffing-box" about the pump 30 rod is avoided, thus contributing to the light running of the pump by removing unnecessary friction. Another object is to provide means whereby the pump rod is maintained in perfect alinement, insuring against binding. 35 And yet another object is to provide a construction wherein any of the working parts or parts subject to wear, or any of the packings can be readily removed and renewed without taking up the pump or re- 40 moving the pipe, or cylinder from the well.

With these objects in view, my invention consists of certain novel features of construction hereinafter described and shown in the accompanying drawings, in which 45 Figure 1, is a side elevation of a pump of the double acting type to which my improvements have been applied. Fig. 2, is a vertical cross section of the pump showing my improvements in place. Fig. 3, is a top plan 50 view of the pump base. Fig. 4, is a top plan view of the base cap. Fig. 5, is a top plan view of a special combined connecting and packing T used in my device. Fig. 6, is a side elevation of a double coupling and packing member. Fig. 7, is a horizontal cross 55

section thereof taken on line 7—7 of Fig. 6. Fig. 8, is a side elevation of a lower pump cylinder partly in section, Fig. 9, is a side elevation of a pump head, and Fig. 10, is a side view of a detail of the pump head.

In the drawings, in which similar reference characters refer to similar parts throughout the several views, I have illustrated the preferred embodiment of my invention and show same as consisting of the 65 base 12 which is provided with the interior compartments 13 and 14, communicating with each other through the port 15. Screw threaded into suitable openings in the upper wall of compartment 13, is the discharge 70 pipe 16, equipped with the spout 17, and also the pipe 18, forming the air chamber and also functioning as a pedestal for the pump head 19. This pump head is provided with the sockets 20, at its upper end and 21, at 75 the lower, which are adapted to receive the guides 22, and 23. These guides consist of the body portion 24, and the rounded shank 25, extending at right angles thereto. The body portion is provided with a rectangular 80 opening adapted to slidably engage the flat bar extension 26^a, of the pump rod 26. With the rounded shanks 25, in the sockets 22, and 23, and with the pump rod centrally suspended with respect to the pump base, these 85 guides are rigidly secured to place by the set screw 27. These two guides alined with the opening in the base cap plug 28, through which the pump rod 26, reciprocates constitute three widely separated bearings, insuring 90 the free reciprocation of the pump rod without binding.

The pump handle 29, may be pivotally secured to the pump head as at 30, through the medium of the fulcrum 31, and pivotally 95 secured to the flat bar extension to the pump-rod 26, as at 32. This flat bar 26^a may also function as a connection of the pump-rod to a wind-mill or other source of power. When the rod is being operated by power the 100 handle may be disconnected by removing pin 33. The free and easy reciprocation of the pump-rod in its bearings is further insured by the brace 34, which securely maintains the guides 22, and 23, in alinement with 105 the opening in the base-cap plug 28.

Screw threaded into the lower portion 35, of the base 12, is the extension casing 36, the length of which is determined by the depth of the frost zone, which naturally varies in 110

different climates, the purpose being, to have it of a length that will bring its lower end well below the frost line. Screw threaded to the lower end thereof is the combined reducing coupling and packing retaining ring 37, which connects the extension 36, to the well casing proper 38, which may be of slightly reduced diameter and which is of a length as determined by the depth of the well, which may be a hundred or more feet deep. To the lower end of the casing 38, the lower cylinder 39, is secured, and to the lower end of this cylinder provision is made for the securing thereto of the usual suction pipe and strainer (not shown).

15 The pump-rod 26, passes loosely through the base-cap plug 28, and is secured to the plunger 40, arranged for reciprocation in the upper cylinder 41. This portion of the 20 pump-rod extending from the flat bar 26^a to the plunger 40, is made of pipe. From the underside of the plunger 40, it extends in jointed sections of convenient length to the plunger 42, in the lower cylinder 39, to which 25 it is securely united. This portion of the rod is made of wood, its natural buoyancy contributing to the ease of operating the pump.

30 In a double acting pump, the water is sucked into the lower cylinder on the up-stroke of the plunger only, and to insure a steady, solid stream of considerable force at the spout or outlet, the upper cylinder 41, is made of a capacity only one-half that of the 35 lower cylinder. On the up-stroke, half of the water is discharged from the spout and the other half passes into the upper cylinder. Then on the down-stroke the upper plunger forces the water out of this cylinder 40 through the spout, thus maintaining a solid, steady stream.

45 Centrally located within the chamber 14, of the base 12, is the T casting 42, with the barrel of the T extending vertically and the branch horizontally. This T is rigidly held centrally of the chamber 14, by forcing the outer end of the branch portion of the T solidly against the face of the port 15, through the medium of the set screw 43, 50 tapped into the wall of the chamber 14, at a point diametrically opposite the port 15. The back of the vertical barrel of the T being provided with the counter sunk lug 44, forming a seat for the end of the set screw.

55 By inserting a ring packing 45, between the flange 46, and the face of the port 15, a water tight joint is effected between the T casting and the chamber 13, by screwing the set screw 43, solidly against the lug 44. This 60 also rigidly secures the T casting in proper position within the chamber 14. Slidably connected to the lower opening of the T, by the packing gland 47, which has a threaded engagement with the outer surface of the 65 lower end of the T, is the water pipe 48.

This pipe has a screw threaded connection at its lower end with a special shaped double connection 49. This special connection consists of the outer barrel 50, and the inner barrel 51, the two being connected at their center of length by the conduits 52-52, affording communication from the interior of the inner barrel 51, to the exterior of the outer barrel 50. Near the lower end of the barrel 50 and exteriorly thereof, is the annular flange 51^a, for engagement with the ring packing 51^b, seated on the flange 51^c, formed 70 75 75 interiorly of the reducing connection 37.

Screw threaded into the upper end of the inner barrel 51, is the connection or spreader pipe 53, which passes through the water-pipe 48, and is centrally located with respect thereto and is of such external diameter as to leave an annular chamber or space between its external face and the interior of the water pipe for the free passage of a thin sheet of water. Its upper end passes on through the T casting 42, with the upper end of which, it has a slideable water tight engagement through the medium of the 80 packing gland or stuffing box 54. The upper end of this pipe terminates in the enlarged head 55, seated within a recess formed in the under side of the base-cap plug 28.

Extending upwardly from the upper edge 85 of the chamber 14, are the three hook shaped lugs 56. The chamber 14, is closed by the base-cap 57, which is securely locked in position by turning the three lugs 58, under the hooked lugs 56. It is provided with 90 the central opening 59, into which the plug 28, is screwed. With the cap securely locked to the base and the plug contacting the end of pipe 53, the pipe will be forced 95 downwardly on screwing the plug into the 100 cap, causing the packing ring 51^a, to seat firmly against the packing 51^b. The upper cylinder 41, is secured in proper position by the reducing coupling 60, which is 105 screw threaded to the pipe 61, which in turn 110 is threaded to the lower end of the inner barrel 51. It will be observed that the pump-rod 26, is loosely suspended from the 115 pump handle or wind-mill gearing for free vertical reciprocation, unimpeded by friction arising from packing glands or stuffing boxes at any point in its length.

In operation, the casing 38, is filled with water at all times, and on each up-stroke of the pump rod, one half of the water raised 120 by the lower cylinder 39, passes into the upper cylinder 41, and the other half passes around the outside of connection 60, through the special connection 49, by passing around the outside of the inner barrel 125 51, and through the water pipe 48, in a thin sheet on the outside of the connecting pipe 53, into the T casting 42, and out of the horizontally extending branch, through the port 15, into the chamber 13, and from 130

thence through the discharge pipe 16, out through the spout 17.

On the down stroke, the plunger 40, forces the water out of cylinder 41, on out to the discharge spout, thus maintaining a solid steady stream at the spout. When the operation of pumping ceases, all the water standing in the discharge pipe 16, chamber 13, T casting 42, water pipe 48, and special connection 49, immediately flows back out of the frost vent 62, thus thoroughly draining the entire pump to a point below the frost line, preventing freezing.

As the body of water from the vent 62, out to the discharge spout is in the form of a thin circular sheet of a volume as defined by the space between the outer surface of the connecting pipe 53, and the interior surface of the water pipe 48, no more than one upward stroke of the pump will be required to raise the water to the point of discharge, regardless of the depth of the well. An exceedingly quick acting pump is thus produced.

If water happened to seep past the plunger 40, which is likely on the wearing of the leather packing, instead of this water following along the pump-rod 26, filling the connecting pipe 53, and freezing the pump-rod solidly therein, this seepage will pass up through pipe 61, into the inner barrel 51, of the special connection 49, and out of the conduits 52, into the reducer 37, from which it will pass out through the opening 63, provided for the purpose. It is thus to be seen that no water can remain in the pump above the frost line, when the pump is not in operation.

The lower cylinder consists of the body or barrel 39, provided with the brass lining 64. Screw threaded to the lower end of the cylinder is the cylinder cap 65, which is provided with the valve seat 66. Seated thereon is the check valve 67, provided with the four depending lugs 68, the inner faces of which are recessed to receive the free ends of the two looped spring wires 69, which cross each other at right angles and have the form of half of an ellipse. When the valve is on its seat, these wires extend entirely below the seat and are free to expand a distance somewhat greater than the internal diameter of the seat, but upon a slight upward pull, they will contract sufficiently to pass through the seat, thus permitting the valve to be raised slightly from the seat or be removed entirely. Extending upwardly from the valve is the threaded shank 70. The plunger consists of the cage 71, and the usual leathers 72. The lower end of the cage is provided with the yoke member 73, having a threaded opening 74, in alignment with the threaded shank 70, of the check valve. Inside of the cage 71, the puppet valve 75, provided with

the vertical leg 76, is arranged for free vertical reciprocation, whereby it will seat on a seat provided in the cage on the up-stroke and lift off the seat on the down stroke.

One of the principal features in the design of the pump is the relative size, arrangement and connection of parts whereby the entire internal mechanism can be readily removed and replaced with very little effort and with the aid of an ordinary monkey wrench only. To remove the parts for renewing the packing, replacing worn leathers or making other repairs, the handle 29, is detached and the pump bar guides 22, and 23, are removed from their sockets 20, and 21. The base cap plug 28, is then unscrewed and the base cap 55, turned out of engagement with the lugs 56.

The pump-rod 26 is then pushed down until the plunger 71, in the lower cylinder 85 strikes the valve 67, then by turning same to the right it will screw onto the threaded shank 70, and as this shank passes through the threaded opening 74, and contacts the end of the puppet valve leg 76, the valve 90 will be forced off its seat and the entire body of water in the pump will rest on the lower valve 67. Then by slightly lifting the pump-rod the valve will be raised off its seat, permitting the water to rush back into the well, washing off the valves, removing any sediment that may have settled on them and avoiding the necessity of lifting the entire body of water contained in the pump when bringing the valves to the surface.

After the water has drained out, a slight upward jerk on the pump-rod, the lower valve will be pulled off its seat, the wire springs 69, compressing sufficiently to pass through the seat. Then upon removing the set screw 43, which holds all the remaining parts in suspension, the rod and all the inside parts can be drawn up.

Having thus described my invention, what I claim is:

1. In combination with a pump casing, a check valve frictionally held in position in the lower end thereof, a plunger provided with a valve, and means whereby the plunger may be interlocked with said check valve and at the same time open the valve in the plunger, whereby the check valve may be lifted off its seat and the water above the plunger allowed to drain through the plunger and past the valve, for the purpose set forth.

2. In combination with a pump casing, a check valve frictionally held in position in the lower end thereof, a plunger provided with a valve, and means whereby the plunger may be interlocked with said check valve and at the same time open the valve in the plunger, whereby the check valve may be lifted off its seat and the water above the plunger allowed to drain through the plun-

ger and past the valve, the check valve being provided with an upstanding threaded stem and the plunger being provided with a depending threaded ring for engaging 5 said stem.

3. In combination with a pump casing, a check valve frictionally held in position in the lower end thereof and provided with an upstanding threaded stem, a plunger 10 provided with a valve having a depending stem and also with a depending internally-threaded ring, whereby the plunger may be interlocked with the stem of the check valve and this stem may be made to contact with 15 the depending stem of the valve in the plunger and hold the same open, for the purpose set forth.

4. In a pump of the character set forth, a pump base, a T-casting and means for removably supporting the same in the pump 20 base with its horizontal branch in communication with the outlet thereof, a pump rod extending down through said casting out of contact therewith, a pipe surrounding the 25 pump rod and having packed sliding connection with the upper end of said pipe, and a water pipe surrounding the aforesaid pipe and having a packed sliding connection with the lower end of said T-casting, 30 the pump base being provided with a movable cap through which said pump rod extends.

5. In a pump of the character set forth, a pump base, a frost casing depending therefrom, a well casing and a connection attaching the same to the lower end of the frost casing, the interior of said connection being provided with a packing seat, a pump rod, a pipe surrounding the pump rod, a 40 water pipe surrounding said aforesaid pipe, a head attached to the lower ends of said pipes and provided with a lateral leak-discharge opening, a packing ring inserted between the lower end of said head and said 45 packing seat in the connection, and means whereby said pipes and said head may be forced downwardly independently of the

50 pump rod to make an annular water-tight joint at the packing, for the purposes set forth.

6. In combination with a pump base provided with a removable cap, a T-casting inclosed in said pump base, a depending frost casing, a well casing and a connection between the same and the lower end of said 55 well casing, said connection being provided with an interior packing seat, a pipe surrounding the pump rod and having a sliding connection with the upper end of the T-casting, a water pipe surrounding the 60 upper end of the aforesaid pipe and having a sliding connection with the lower end of the T-casting, a head attached to the lower ends of said pipes and adapted to seat against said packing seat in the connection 65 and provided with a lateral leak-discharge passage, and means on said cap for pressing downwardly on the upper end of said inner pipe, for the purposes herein set forth.

7. In a pump of the character set forth, 70 a pump base, a frost pipe depending therefrom, a well casing, a cylindrical member connecting the same to the lower end of the frost pipe, this member being provided with an annular seat in its interior and also with a leak-opening, a piston rod extending down through the pump base and frost pipe and connecting member, a head adapted to seat 75 down against the seat on the interior of the connecting member, two concentric pipes connected to said head, a T-casting inclosed in the pump base and having communication 80 with the outlet thereof, the inner one of said pipes extending up through said T-head and the outer one of said pipes having communication with the outlet of said T-head, and means whereby the inner pipe 85 may be pressed downwardly to cause the seating of the aforesaid head, for the purposes set forth.

90 Signed by me at Davenport, Iowa, this 24th day of November, 1915.

TIMOTHY STEBBINS.
